UNITED STATES PATENT OFFICE.

RUSSELL B. HOWARD, OF WINDHAM, VERMONT.

REPLAYING DEVICE FOR TALKING MACHINES.

Application filed July 22, 1920. Serial No. 398,094.

To all whom it may concern:

Be it known that I, RUSSELL B. HOWARD, a citizen of the United States, residing at Putney, in the county of Windham and 5 State of Vermont, have invented a new and useful Replaying Device for Talking Machines, of which the following is a specification.

The principal objects of this invention 10 are to provide a simple and practical device by which a talking machine, phonograph, or the like, can be caused to play and replay a record as long as may be desired; to provide a device of this character which can be 15 adjusted very simply to provide for records of different lengths, adjustments being arranged for at both ends of the record; to provide connections on a shaft operated by the motor shaft for initiating the various 20 operations or controlling them; to provide automatic means for throwing said devices in and out of operation; to provide an improved and simplified means for lifting the stylus from the record and lowering it back 25 into operative playing position; to control the mechanism therefor by locating it in the tone arm; to provide a convenient device for swinging the tone-arm back from the stopping position to the starting position; to 30 provide means connected with the last named mechanism for controlling the stopping of the said shaft and for locking the shaft starting connections; and in general to provide means for accomplishing these several 35 purposes associated with each other in a convenient way so that they can be applied to an ordinary machine without material modifications. Further objects and advantages of the invention will appear herein- 40 after.

Reference is to be had to the accompanying drawings in which—

Fig. 1 is a plan of a talking machine of one type showing such features of this invention as are applied on the top of the casing;

Fig. 2 is a sectional view on the line 2—2 of Fig. 1, showing the tone-arm and its connected parts in side elevation;

Fig. 3 is a plan on enlarged scale of the

mechanism shown in Fig. 1 with the tone-arm removed;

Fig. 4 is a sectional view on the line 4—4 of Fig. 5, which is an elevation of the mechanism for lifting the sound box; 55

Fig. 6 is a sectional view on the line 6—6 of Fig. 1;

Fig. 7 is an end elevation of the parts shown in Fig. 6;

Fig. 8 is a sectional view on the line 8—8 60 of Fig. 6;

Fig. 9 is a side elevation of the clutch mechanism;

Fig. 10 is a sectional view on the line 10—10 of Fig. 8; showing the clutch lock- 65 ing mechanism in plan;

Fig. 11 is a sectional view on the line 11—11 of Fig. 7 showing part of the clutch locking mechanism;

Fig. 12 is a plan taken above the cover 70 of the casing showing a part of the locking mechanism;

Fig. 13 is a sectional view on the line 13—13 of Fig. 8;

Fig. 14 is a sectional view on the line 75 14—14 of Fig. 13;

Fig. 15 is a sectional view on the line 15—15 of Fig. 7;

Fig. 16 is a plan taken above the cover of the controlling mechanism, shown in a different position from that in which it appears in Fig. 3;

Fig. 17 is a sectional view on the line 17—17 of Fig. 16;

Fig. 18 is an end view of the tone arm 85 moving elements, and Fig. 19 is a sectional view on the line 19—19 of Fig. 15.

This invention, either in the form shown or in some equivalent form, is capable of being applied to various kinds of talking 90 machines and the like, including those having positive feeding means for shifting the tone arm across the record. I have not thought it necessary to illustrate it in connection therewith but have shown it only 95 as applied to a machine of the well known type in which the tone arm is shifted by the travel of the stylus in the groove on the playing record. An example of this is shown in the drawings as comprising a 100

casing having a cover 11 provided underneath with a motor 12 having a governor 13 which is controlled by any well-known device for that purpose. This motor in the usual way operates a spiral gear 14 which runs a worm 15 that is mounted on and forms part of the shaft 16 which rotates the record supporting table 17 on which is located the record R.

10 For the purpose of this invention I have provided a shaft 20 parallel with the motor shaft 19 on which a gear 21 is mounted. This drives a smaller gear or pinion 22 on a parallel shaft 23. This shaft carries a gear or pinion 24 adapted to mesh with a gear 25 slidably mounted on the operating shaft 20. This gear 25 has a sliding sleeve 26 through the hub of which extends an oblong slot 27. Into this projects a stud 28 fixed to the shaft 20. This sleeve is also provided with a disc 29 having a cam projection 30. These elements constitute a sliding clutch.

25 A spring 31 operating against a collar 32 fixed on the shaft 20 normally pushes the disc 29 and gear 25 to the right in Fig. 6, so that the gear will tend to mesh with the gear or pinion 24 and the shaft 20 will be positively operated whenever the sliding 30 sleeve is free to move.

35 On a bracket 33 fixed on the bottom of the cover 11 is pivoted a lever 34. This is provided with a downwardly extending projection or stud 35 normally held up in inoperative position by a spring 36. It is however capable of being pushed down in opposition to that spring so as to come into the path of travel of the cam projection 30. In that case this lever, not being 40 adapted to swing except on the horizontal pivot 37, will push the structure embodying the parts 25, 26 and 29 back against the spring 31 into the position shown in Fig. 6, thus disconnecting the element 25 from 45 the motor and preventing the operation of the mechanism which constitutes the principal part of this invention.

50 Mounted on the shaft 20 are two cams 38 and 39. On each of these cams rests a lever, 40 and 41 respectively. These levers are guided in a bracket 42 having slots for that purpose and located on the bottom of the cover 11. On this bracket is pivoted a lever 43 which has a downwardly extending 55 portion 44 resting on the lever 40. The other end of the lever 43 projects over the free end of the lever 34. When the high part of the cam 38 raises the lever 40 the lever 34 is depressed and the projection 35 moved 60 down into a position to engage the cam projection 30. This performs the function of stopping the shaft 20 as stated, but at other times the spring 36 holds these parts up and permits of the full operation of the device.

65 The lever 40 also has other functions. It is

connected by a spring 46 and hook 47 forming a lost motion connection with a lever 48 which has a wedge-shaped operating end 49. When the lever 40 rises it first operates the lever 43 to depress the lever 34. Then, when 70 the spring 46 is fully compressed, a pin on the top of the lever 40 engages and positively moves the left-hand end of the lever 48 up, depresses the wedge 49, and forces it against the slanting side of the end of an 75 arm 50. The latter is thus forced back against a spring 51 mounted on a pin 52. The result of this is to force a depending projection or latch 53 on the arm 50 to the right into the position shown in Fig. 8. 80 There it comes over a notch 54 on the end of the lever 34 and locks that lever down in its position for stopping the mechanism when the cam 38 completes a revolution.

When the cam 38 is moving from its 85 higher position to the lower one the lever 40 begins to be depressed. The first action of this is to cause the hook 47, after an idle downward motion, to come into contact with the lever 48 as indicated in Fig. 11 and draw 90 the wedge 49 up away from the arm 50. This then allows the projection or latch 53 to move to the left in Fig. 8 and releases the lever 34. Then the spring 36 lifts the lever 34 and removes the projection 35 from the 95 path of the cam 30. This allows the shaft 20 to operate until the cam 38 comes around to its lowermost position.

This cam 38 and lever 40 also have another function. Connected with the end of the 100 lever is a chain or other convenient connection 56 which is connected with the lower end of a lever 57 pivoted on a stud 58 on a bracket 59 supported from the cover 11. The upper end of this lever has a comparatively wide range of motion. It extends up to a point just below the lower surface of the cover and is connected by a link 60 with a horizontal slide 61 operating in guideways 62 mounted on the bottom of the cover 11. 110 This slide is arranged in the present instance at the rear of the machine, and is provided with a spring 63 for drawing it back when the lever and flexible connection 56 allow that action to take place.

115 On this slide is a shaft 64 extending up through the cover 11. This shaft is shown as vertical and is provided with an arm 65 connected by a spring 66 with the link 60 to turn the shaft always in one direction 120 until it engages a stop 67. Therefore it will always turn it back to that position when for any reason it is ever turned away from it.

The shaft 64 extends through a slot 70 in the cover 11 parallel with the slide 61, and is 125 provided with an arm 71 lying over the cover 11 and adapted to engage a downwardly extending stud 72 on the tone arm 73 for operating the same on its pivot at 74.

130 It will be seen therefore that the operation

- of the mechanism just described will act to move these parts to the right in the figures and swing the tone arm from the position in which it has completed the playing of a record back to the starting position indicated in Fig. 1. Yet the action of this projection 5 is cushioned by the spring 66, so that the tone arm is not suddenly put into action or suddenly stopped.
- 10 I have shown an adjustable stop 75 pivoted on a stud 76 and yieldingly held in its adjusted positions by a spring 77 or friction device. This constitutes a very simple means for adjusting the point at which the 15 playing is to be commenced and constitutes a stop for limiting the motion of the tone arm in that direction.

It will be understood that when the tone arm is left in its starting position as shown 20 in Fig. 1 and the record is played, it will be gradually moved over to its limiting position, that is, the position at which the record stops. If it engages the arm 71 during this 25 action this arm will yield on account of the presence of the spring 66, even if the operation of this arm is not completed at that time. This constitutes a valuable safety feature. But whether it engages this arm or not it will eventually touch an adjustable 30 limit gauge 80. This is shown in the form of a member mounted on an arm 81 having an adjusting slot 82 through which it is secured by a screw 83 to an oscillatable lever 84. The arm 81 is 35 also pivotally mounted at 85 on an oscillatable arm 86 having a handle 87 for operating the whole device. These two arms 84 and 86 are shown as pivoted on a screw 87^a on the cover 11, and a spring 88 is provided 40 for yieldingly pulling this whole element over to the right. The limit gauge 80, being adjusted properly in accordance with the point at which the record stops, the spring 88 will pull the whole structure over 45 until a tooth 89 enters a notch 90 in a lever 91 which is mounted on the upper end of a shaft 92 that passes down into the casing.

I have shown the machine as provided 50 with the usual brake which consists of a three-armed lever 95 having a brake member 96 for engaging on the inside of the downwardly extending flange on the record supporting table 17. This is controlled by a spring 97 limited by a stop 98 working in 55 a slot 99 in this arm. These parts are well known. I have, however, provided a stud 100 and freely pivoted thereon is a lever 101 having a stud 102 extending upwardly from each end. Either end of this lever is adapted 60 to be engaged by one of the arms of the brake lever 95, and when the brake is on as shown in dotted lines in Fig. 3, it will be held by it in the position shown therein. In this position the stud 102 at the other end engages the end of the lever 91 and prevents 65

its moving back even if the tooth 89 moves away from the notch 90. But when the brake lever is turned to the off position shown in full lines in Fig. 3, this influence is removed and the lever 101 has no effect. 70

The shaft 92 on which the lever 91 is fixed extends down through the cover 11 and is provided on its lower end with the arm 50 having the projection 53 thereon. When released by the withdrawal of the 75 tooth 89 the spring 51 will force the projection 53 away from the notch 54 thus turning the shaft 92 and consequently the arm 50. This allows the lever 34 to rise and the clutch to be thrown in to start this mechanism. 80

Having described the mechanism for starting and stopping the repeating apparatus and for moving the tone arm back from the position in which it is left when the selection has been played to that in which it is ready to start in over again, I will now describe that for lifting the sound box and stylus. This is operated by the cam 39 and lever 41. Pivotedly connected with this lever is a link 110 which depends therefrom and is pivoted at its lower end to a lever 111. The pivotal connection in this case is shown as involving a bent end 112 on the link 110. This lever 95 111 is pivoted at 113 to a bracket 114 on the casing 10 and it extends into the sound conduit or air channel 115 which communicates with the tone arm 73 above, of course being hollow. The free end of this lever 100 111 passes into a slot in the end of a lever 116 pivoted inside the air channel. This is provided with a flexible connection shown in the form of a chain 117 at its opposite end. This passes up the vertical portion of the 105 sound conduit and is connected at its top inside the hollow arm 73 with an arm 118 mounted on a shaft 119. This shaft extends out through the side of the tone arm and has an arm 120 fixed to its projecting end. This arm has an eye 121 through which passes a link 122 having a head 123 so that it is slidably connected with the arm 120. On the end it is provided with a bent end or hook 124 extending into a slot 115 in an arm 125 fixed to the sound box supporting frame 126. The action of these 128 parts to lift the sound box 127 and stylus off the record will be obvious.

The operation of the machine is as follows:—When it is desired to start to play and repeat, the brake 95 is turned to the off position shown in full lines in Fig. 3 and the two stops 75 and 80 are adjusted properly according to the length of the record 125 to be played and repeated. The stud 72 has to be brought into position between the stop 75 and the arm 71 in order to get the stylus into proper position for playing. The usual starting device is then operated to start the 130

machine and the playing takes place in the usual manner. The shaft 20 normally performs no function while the selection is being played. As the stylus travels across the record the stud 72 moves over the path indicated by its dotted line positions in Fig. 3 from the one at the right to the one at the left. When it reaches the one shown at the left it engages the stop 80 and pushes it back, releasing the tooth 89 from the notch 90. The lever 101 is free at this time and presents no obstacle to the action of this element. This allows the shaft 92 to be turned slightly by the spring 51 so as to move the projection or latch 53 to the left in Fig. 8 and permit the lever 34 to be raised by its spring 36, this having been locked previously in its depressed position. But before the shaft 20 was stopped previously the lever 48 had been pulled down at the left and up at the right by the fact that the lever 40 rested on the low part of the cam 38. This is indicated in dotted lines in Fig. 11. The result of this is that the projection 35 on the lever 34 is moved up away from the projection 30 on the cam disc 29. Therefore the spring 31 pushes the gear to the right in Fig. 6 and keeps it in mesh with the constantly rotating gear 24. From that point on the shaft 20 will continue to rotate throughout a complete revolution or until the projection 35 again moves down into the position to withdraw the gear 25. Then the shaft 20 will stop.

The repeating mechanism having been started into operation in this way the first effect of it is for the cam 39 to raise its lever 41. The cams 38 and 39 are so located and shaped that this occurs while the arm 40 is resting on the low part of its cam 38. The ascent of the lever 41 raises the link 110 and draws down the chain 117 so as to swing the shaft 119 slightly and pull the link 120 to the left in Fig. 2, causing the arm 125 to swing with it and the sound box 127 to turn upwardly on its pivot. The cam 39 is so shaped that these parts will remain in the position in which they are thus placed throughout a large proportion of the revolution of the shaft 20.

As soon as the sound box is raised the cam 38 comes into action and raises its arm 40. This has several effects. In the first place it releases the lever 48 and moves it back to the full line position shown in Fig. 11, so that the wedge 49 comes down into contact with the arm 50 and is forced by the positive action of the lever 40 to move this arm back against the spring 51. This swings the shaft 92 back so that the tooth 89 will enter the notch 90 and move the projection or latch 53 over into the full line position shown in Fig. 8 to lock the lever 34 down against the action of the spring 36 and leave the projection 35 in the path of the cam

projection 30. Before this takes place, the ascent of the lever 40 has resulted in raising the projection 44 on the lever 43 and thus depressing the other end of that lever which extends over the arm 34 and depresses that arm into the position shown in full lines in Fig. 8. It is then locked in position as stated. The parts are thus left in position for repeating.

The ascent of the arm 40 also raises the flexible connection 56 and swings the lever 57 from the full line position in Fig. 15 to the dotted line position. This, through the action of the connections above described, moves the slide 61 in the same direction. This slide as stated has pivoted upon the arm 71 and that is in the path of the stud 72, so this action moves the tone arm, through its stud 72, back to the starting position.

It is at this point that the cam 39 allows the lever 41 to drop and the sound box is then automatically dropped down so as to replace the stylus in playing position. This is done through the connections extending up through the air passage and tone arm.

It will be noted that the position in which the stylus is lowered on the record is determined by the position of the stop 75 which is adjusted before the playing commences. It will also be noticed that the position in which the stylus is located when the repeating mechanism starts to operate is controlled by the limit gauge 80 which is likewise adjusted at the beginning.

The replacing of the stylus on the record at the commencement of the same is finally accomplished at about the time the cam projection 30 engages the projection 35 and forces the disc 29 back so as to stop the rotation of the shaft 20. It will be understood of course that the motor operates continuously throughout all this action and also the shafts 23 and 20. The brake 95 is put on to stop replaying.

In this way a positive acting mechanism is provided which can be applied with minor changes to all types of talking machines and the like and will be certain to operate for the purposes specified. It is also provided with yielding connections to avoid any interference of the several operative parts even if something should happen to the mechanism to disarrange it and cause it to operate slightly out of its proper order. However, the mechanism is so designed that such an accident could not occur except by the interposition of some foreign body or the dislocation of some of the parts by an accident such as would be likely to throw any kind of machinery out of order.

Although I have illustrated and described only a single form of the invention and shown it as applied to only one type of phonograph I am aware of the fact that modifications can be made therein and that

it can be applied to other types of machines by persons skilled in the art without departing from the scope of the invention as expressed in the claims. Therefore I do not 5 wish to be limited to the particular machine shown herein or the details of construction, but what I do claim is:—

1. In a talking machine, the combination with an operating motor and a tone arm, 10 of an element operated by the motor, yielding means for constantly tending to hold said element in condition for being operated by the motor, positive means for disconnecting said element from the motor, means operated by the motion of the tone arm for rendering said disconnecting means inoperative, and means operated by said element for moving the tone arm to a position to repeat.
2. In a talking machine, the combination with an operating motor and a movable tone arm, of an element operated by the motor, means for directly and positively disconnecting said element from the motor after a 25 cycle of operations has been completed, adjustably located means operated by the motion of the tone arm for moving said disconnecting means into inoperative position, and thus permit the said element to continue to operate through a second cycle, and means operated by said element for moving the tone arm to a position to repeat.
3. The combination with a talking machine and the motor for operating it, of a 35 replaying operating element, means for connecting said element with and disconnecting it from the motor comprising a rotary cam mounted to move in an axial direction and a lever having means adapted to lie 40 in position to cause the cam to move as it turns, means for locking said lever in operative position, and means operated by the tone arm of the machine as it moves to its limiting position after playing a selection 45 for releasing said lever and permitting it to move from said operative position, whereby said operating element will begin its operation.
4. The combination with a talking machine and the motor for operating it, of a 50 shaft, means for connecting said shaft with and disconnecting it from the motor comprising a cam mounted to move and a lever having means adapted to lie in position 55 to cause the cam to move as it turns, means for locking said lever in operative position, and means operated by the tone-arm of the machine as it moves to its limiting position after playing a selection for releasing said lever and permitting it to move 60 from said position.
5. The combination with a talking machine, a motor for operating it, and a swinging tone-arm, of a replaying mechanism, a sliding clutch connecting said mecha-

nism with the motor and disconnecting it therefrom, a cam constituting a part of said clutch, means adapted to lie in the path of said cam for positively drawing the cam and clutch back out of the clutching position, a latch for holding said means in operative position, and means operated by the tone arm for releasing said latch and allowing the said means to move into inoperative position.

6. In a replaying device for a talking machine, the combination with a motor for operating the machine, and a swinging tone-arm, of replaying connections, a clutch for connecting said replaying connections with the motor and disconnecting them therefrom, a cam for operating said clutch, means adapted to lie in the path of said cam for drawing the cam and clutch back out of the clutching position, a latch for positively holding said means in operative position, means operated by the tone-arm for releasing said latch and allowing the cam operating means to move into inoperative position, and yielding means for moving said cam operating means to inoperative position when released.

7. In a talking machine, the combination with a swinging tone-arm, of a shaft having replaying connections, a sliding clutch on said shaft for connecting it with a source of power and disconnecting it therefrom, a lever having means for positively drawing the clutch back out of clutching position, a latch for holding the lever in operative position, means operated by the tone-arm for releasing said latch, and means operated by the shaft for positively moving the lever into inoperative position.

8. The combination with a talking machine, a motor for operating it, and a swinging tone arm, of a shaft, replaying connections operated by said shaft, a sliding clutch on said shaft for connecting it with the motor and disconnecting it therefrom, a cam constituting a part of said clutch and rotating with the shaft, a lever having means adapted to operate said cam for drawing the clutch back out of the clutching position, a latch for holding the lever in operative position, a movable stop adapted to be operated by the tone arm at the end of a selection and having a tooth, a lever having a notch for normally receiving said tooth, and means for turning said lever from the position in which it holds the first named lever locked in its operative position, whereby when the tooth is withdrawn from the notch the last named means will be free to act.

9. The combination with a talking machine, a motor for operating it, and a swinging tone-arm, of a shaft, replaying connections actuated by said shaft, a clutch for connecting the shaft with the motor and dis-

connecting it therefrom, a cam for operating said clutch, a lever having means for positively drawing the cam and clutch back out of the clutching position, a latch for holding the lever in operative position, a spring for moving said lever back, means operated by the tone arm for releasing said latch and allowing the lever to move into inoperative position, and means operated by said shaft 10 for positively moving said latch into its latching position.

10. The combination with a talking machine, and a motor for operating it, of a shaft having replaying connections, a sliding clutch on said shaft for connecting it with the motor and disconnecting it therefrom, a cam constituting a part of said clutch and rotating with the shaft, a lever having means adapted to lie in the path of said cam for positively drawing the cam and clutch back out of the clutching position, a latch for holding the lever in operative position, means operated by said shaft 20 for positively moving said latch into its locking position and holding it there, means for positively withdrawing said latch moving means thereafter, and yielding means for forcing the latch into inoperative position to release the lever.

30. 11. The combination with a talking machine, its operating motor and movable tone-arm, of a shaft, replaying means operated by said shaft, means for connecting said shaft with and disconnecting it from the motor, a lever having a projection, a cam controlling the connecting means and movable in the path of said projection, a spring for forcing said cam and connecting means into operative position to connect the shaft 35 with the motor, said projection being adapted to hold the cam and connecting means in inoperative position, yielding means for moving said lever to a position to remove the projection from the path of the cam, a lever having its end engaging the first named lever, and means on said shaft for positively operating the latter lever to force the first named lever into operative position.

50. 12. The combination with a talking machine, its operating motor and movable tone arm, of a shaft, a clutch for connecting said shaft with and disconnecting it from the motor, means operated by the tone arm for 55 controlling the actuation of said controlling means when the selection has been finished, said means comprising a lever having a projection, a cam connected with the clutch and movable in the path of said projection, means for yieldingly forcing said cam and clutch into operative position, said projection being adapted to positively hold the cam and clutch in in-operative position, yielding means for moving said lever to a 60 position to remove the projection from the

path of the cam, a second lever having its end engaging the first named lever, means on said shaft for positively operating the latter lever to force the first named lever into operative position, the first named lever 70 having a notch, an arm provided with a projection adapted to engage said notch and hold the first named lever in operative position, a spring for normally holding said arm and projection out of the way of said notch, and means for engaging said arm and positively forcing it against the spring into position to engage in the notch.

13. The combination with a talking machine, its operating motor and a shaft, a clutch for connecting said shaft with and disconnecting it from the motor, a lever having a projection, a cam connected with the clutch and movable in the path of said projection to positively hold the cam and clutch 85 in in-operative position, a second lever engaging the first named lever, means on said shaft for operating the latter lever to force the first named lever into operative position, the first named lever having a notch, an arm adapted to engage said notch and hold the first named lever in operative position, and means for engaging said arm and positively forcing it into position to engage in the notch.

14. The combination with a talking machine, its operating motor and movable tone-arm, of a shaft, a clutch for connecting said shaft with and disconnecting it from the motor, a lever having a notch, a cam connected with the clutch and movable in the path of said lever to hold the cam and clutch in position to connect the motor with the shaft, yielding means for moving said lever from the path of the cam, means for engaging the lever, means on said shaft for positively operating the engaging means to force the lever into operative position, an arm adapted to engage said notch and hold the lever in operative position, said arm arranged to be retracted after it has been operated, a stop adapted to be operated by the tone arm when it reaches the end of a selection, means connected with said stop for holding the arm locked in operative position 115 to hold the lever in position to actuate the cam, and means whereby when the tone arm reaches the position for completing the playing of the selection the arm will be released so that it can move out of the way and permit the lever to move out of operative position.

15. The combination with a talking machine, its operating motor and movable tone arm, of a shaft, clutching means for connecting said shaft with and disconnecting it from the motor, a lever having a notch, a cam connected with the clutching means and movable across the path of said lever, an arm provided with a projection adapted to 125

- engage said notch and hold the lever in operative position, a spring for normally holding said arm out of the way of said notch, means for retracting said arm after it has been operated by the spring, a stop adapted to be operated by the tone arm when it reaches the end of a selection, means connected with said stop for holding the arm locked in operative position to hold the lever in position to actuate the cam, and means whereby said stop can be adjusted to provide for throwing the clutch and stopping the shaft at any desired point in the path of travel of the tone arm.
16. The combination with a talking machine, its operating motor and movable tone arm, of a shaft, clutching means for connecting said shaft with and disconnecting it from the motor, a lever having a projection adapted to positively hold the clutching means in inoperative position, a cam connected with the clutching means and movable in the path of said projection, a spring for forcing said cam and clutching means into operative position, yielding means for moving said lever to a position to remove the projection from the path of the cam, a movably mounted stop adapted to be actuated by the tone arm during its travel provided with a tooth, a lever having a notch for receiving said tooth, a brake, and means connected with said brake for preventing the actuation of the last named when the brake is on.
17. The combination with a talking machine, its operating motor and movable tone arm, of a shaft, clutching means for connecting said shaft with and disconnecting it from the motor, means operated by the tone arm for controlling the actuation of said clutching means when the selection has been finished, the last named means comprising a lever having a projection, a cam connected with the clutching means, a spring for forcing said cam and clutching means into operative position, said projection being adapted to positively hold the cam and clutching means in inoperative position, yielding means for moving said lever to a position to remove the projection from the path of the cam, a lever having its end engaging the first named lever, means on said shaft for positively operating the latter lever to force the first named lever into operative position, said means operated by the tone arm being provided with a tooth, a relatively movable notch for receiving said tooth, a brake, a freely movable member adapted to be engaged by the brake and having means for preventing the actuation of said notch when the brake is on.
18. The combination with a talking machine, its operating motor and movable tone arm, of a shaft, means for connecting said shaft with and disconnecting it from the
- motor, means operated by the tone arm for controlling the actuation of said clutching means comprising a projection, a cam connected with the connecting means and movable in the path of said projection, said projection being adapted to positively hold the cam and connecting means in inoperative position, yielding means for moving said projection to a position away from the path of the cam, a lever adapted to actuate said projection, means on said shaft for positively operating the lever to force the projection into operative position, and means actuated by said shaft for moving the tone arm back across the record after the shaft starts.
19. The combination with a talking machine and the motor for operating it, of a shaft, means for connecting said shaft with and disconnecting it from the motor comprising a cam mounted to move and a lever having means adapted to lie in position to cause the cam to move as it turns, means for locking said lever in operative position, means operated by the tone arm of the machine as it moves to its limiting position after playing a selection for releasing said lever and permitting it to move from operative position, a second cam on said shaft, a lever actuated by the last named cam, and means connected with the last named lever for swinging the tone arm back across the record after the shaft starts.
20. The combination with a talking machine, the motor for operating it, and a tone arm adapted to swing to move a stylus across the record, of a shaft, a cam on said shaft, a lever operated by said cam, means operated by said lever for positively disconnecting the shaft from the motor when the shaft has completed a revolution, said means comprising a movable member, a lever connected with the first named lever for positively actuating said movable member into operative position for disconnecting the shaft, a latch for holding said member in operative position, means actuated by the first named lever for positively locking said latch, and means operated by the first named lever for moving the tone arm back after the shaft commences to operate.
21. The combination with a talking machine, the motor for operating it, and a tone arm adapted to swing to move a stylus across the record, of a shaft, means for connecting said shaft with the motor to be operated thereby, a lever operated by said shaft, means operated by said lever for disconnecting the shaft from the motor when the shaft has completed a revolution, a latch for holding said means in operative position, means actuated by the lever for positively locking said latch, and means operated by the lever for moving the tone arm after the shaft commences to operate.
22. The combination with a talking ma-

chine, the motor for operating it, and a tone arm adapted to swing to move a stylus across the record, of a shaft, means for connecting the shaft with the motor, a cam on said shaft, a lever resting on said cam, a movable member, a lever connected with the first named lever for positively actuating said movable member into operative position for disconnecting the shaft, a slide, connections 5 from the first named lever for moving the slide in one direction, an arm yieldingly connected with said slide and movable therewith, and a projection on the tone arm in position to be engaged by the said arm on the 10 slide and moved thereby for moving the tone arm back after the shaft commences to operate.

23. The combination with a talking machine, the motor for operating it, and a tone arm, of a shaft, means for connecting said shaft with the motor to be operated thereby, a lever operated by said shaft, means operated by said lever for positively disconnecting the shaft from the motor when the 25 shaft has completed a revolution, a latch for holding said means in operative position, means actuated by the lever for positively locking said latch, a slide connected with said lever to be operated thereby, a shaft 30 pivoted on said slide having an arm projecting therefrom, a spring for holding the shaft yieldingly in its extreme position, and means on the tone arm movable in position to engage said arm to be moved by it.

24. In a talking machine the combination with a motor for operating a record, a freely pivoted tone arm, and a casing in which the machine is mounted, of a shaft adapted to be connected with the motor, a lever operated by said shaft, a slide connected with the lever to be operated thereby, an arm projecting through the casing and movable 40 with said slide, a limit gauge adjustably mounted on the casing and having means by 45 which it will be moved when the tone arm reaches a predetermined position, and means connected with the limit gauge for controlling the connection of the shaft with the motor.

25. In a talking machine the combination with a motor, a tone arm, and a casing in which the machine is mounted, of a shaft adapted to be connected with the motor, a slide connected with the shaft to be operated thereby, an arm projecting through the casing and movable with said slide, a limit gauge mounted on the casing and having means by which it will be moved when the tone arm reaches a predetermined position, and means connected with the limit 55 gauge for controlling the connection of the shaft with the motor.

26. In a replaying device for a talking machine or the like, the combination with a 60 motor and a movable tone arm, of a shaft,

a lever, means on the shaft for operating the lever, a second lever, means operated by the second lever for directly controlling the connection of the shaft with the motor, means operated by the first named lever for positively forcing the second lever into position to disconnect the shaft from the motor, and means operated by the first named lever for locking the second lever in that position. 70

27. The combination with a talking machine, the motor for operating it, and a tone arm adapted to swing to move a stylus across the record, of a shaft, means for connecting said shaft with the motor to be operated thereby, a lever operated by said shaft, 80 means operated by said lever for disconnecting the shaft from the motor when the shaft has completed a revolution, a latch for holding said means in operative position, means actuated by said lever for positively locking 85 said latch, means operated by the lever for moving the tone arm back after the shaft commences to operate, a cam on said shaft, and means connected with and operated by said cam for first lifting the stylus carried 90 by the tone arm.

28. The combination with a talking machine, the motor for operating it, and a tone arm adapted to swing to move a stylus across the record, of a shaft, a cam on said shaft, 95 a lever resting on and operated by said cam, means operated by said lever for positively disconnecting the shaft from the motor when the shaft has completed a revolution, said means comprising a movable member, a lever 100 connected with the first named lever for positively actuating said movable member into operative position for disconnecting the shaft, a latch for holding said movable member in operative position, means actuated by the first named lever for positively locking said latch, means operated by the first named lever for moving the tone arm back after the shaft commences to operate, a second cam 105 on said shaft, and means connected with and operated by said second cam for first lifting the stylus carried by the tone arm. 110

29. In a talking machine the combination of a motor, a tone arm, a sound box for carrying a stylus pivoted on the tone arm, a 115 sound conduit, a shaft adapted to be operated by the motor, a cam on said shaft, a lever extending into the sound conduit and adapted to be lifted by the cam, a shaft carried by the tone arm and having two arms, one inside and the other outside the tone arm, the inside one being connected with the last named lever, and a connection between the outside arm and the sound box for swinging it. 120

30. In a talking machine the combination of a motor for operating it, a casing in which the motor is located, a tone-arm pivotally mounted outside the casing, a sound box for carrying a stylus pivoted on the tone arm, 130

a sound conduit extending through the casing, a shaft in the casing adapted to be operated by the motor, and means operated by said shaft and extending through the sound conduit and tone arm for raising the sound box on its pivot, said means comprising a cam on said shaft, a lever extending into the sound conduit and adapted to be lifted by the cam, a shaft carried by the tone arm and

having two arms, one inside and the other outside the tone arm, the inside one being connected with the last named lever, and a lost motion connection between the outside arm and the sound box for swinging it upon its pivot.

In testimony whereof I have hereunto affixed my signature.

RUSSELL B. HOWARD.
